The ornamental design for a wearable light sensing device, as shown and described.

DESCRIPTION

FIG. 1 is a front perspective view of a first embodiment of a wearable light sensing device;

FIG. 2 is a bottom view thereof;

FIG. 3 is a right side view thereof;

FIG. 4 is a back view thereof;

FIG. 5 is a top view thereof;

FIG. 6 is a front view thereof;

FIG. 7 is a left side view thereof; and,

FIG. 8 is a front perspective view of a second embodiment of a wearable light sensing device, the second embodiment being a mirror image of the first embodiment.

The broken lines depict environmental subject matter only and form no part of the claimed design.
